UNITED STATES PATENT OFFICE

HANS PETER GRONBECH, OF PACIFIC BEACH, CALIFORNIA

SCREEN ROLLER ADJUSTMENT DEVICE

Application filed December 18, 1931. Serial No. 581,882.

This invention relates to an adjusting device for regulating the tension in a roller upon which a screen is wound.

More specifically the invention pertains to one of a series of inventions appertaining to a combination screen and glass window construction, the other inventions having been made the basis of other applications for patent.

10 An important object of the invention is to provide an improved construction whereby the screen-roller-spring may be very quickly adjusted to any tension desired, without removing the roller from its housing. Said improvement including a circular dished ratchet, a spring dog engageable with the teeth thereof and means manually operative through the medium of said ratchet and dog to tension said spring.

15 A further object of the invention is in the provision of simplified means whereby the screen may be held snugly rolled on the roller thus maintaining the proper adjusted tension of the spring when it is desired to remove 25 the roller for repairs or for other reasons.

Still further objects, advantages and features of the invention may also hereinafter appear.

Referring to the accompanying drawing 30 which illustrates what is at present deemed to be a preferred embodiment of the invention,

Fig. 1 is a fragmentary elevational view of the screen roller assembly as applied in its 35 frame and united to a sash, parts being broken away to show interior construction.

Fig. 1a is a fragmentary perspective view showing the means for locking the screen to the sash.

40 Fig. 2 is a mid-sectional view of the roller itself.

Fig. 3 is a right hand elevation of the roller shown in Fig. 2, part of the operating handle being sectioned.

45 Fig. 4 is a fragmentary left hand elevation of the roller shown in Fig. 2.

Fig. 5 is an end view of the roller shown in Fig. 2, part of the supporting bracket being broken away.

Fig. 6 is a fragmentary perspective view of the detached screen and roller.

The invention comprises a roller 8 on which is adapted to be wound and unwound a screen 9, said screen in turn being detachably applied to a sash 10.

55 The specific purpose for which the screen is intended for use, is in conjunction with a sidewise sliding sash, which slides in front of a stationary sash so that when the roller 8 is rotated, it either winds the screen thereupon or the screen is unwound therefrom thus accommodating itself to the position of said sash.

60 The stationary sash (not shown) and the 65 slideable sash 10 are usually formed of separate elements adapted for assembling in an interlocking relation with each other.

The screen 9 is provided with an end strip 11, a portion of which extends laterally from the screen and is provided with an aperture 11a. There is further provided a pivoted locking element 12, provided with an open slot 12a, and there is fastened to the frame 70 of the sash a screw having a locking head 13 with which said locking element 12 cooperates. Said head is adapted to be extended through said aperture, and said locking element through the medium of said slot engaging the shank of the screw between its head and the inside face of the end strip to secure 75 said screen to said sash.

80 Since the patentable structure of this particular combination of sashes and cooperating screens contributes to the subject matter of other applications hereinbefore alluded to and does not form per se a part of the present invention, further remarks relative thereto will be unnecessary.

85 The roller 8 has secured to its upper end a trunnion cap 14 the trunnion portion 15 of which is fed into its seat through a bayonet slot 16 in the plate 17 which forms the lower wall of the housing 18.

90 There is a bracket plate 19 fastened to the upright frame member 20 of the window structure which supports the roller at its lower end, there being an aperture through which the trunnion end portion 21 of said roller extends.

The latter aperture together with the seat in which the trunnion cap 14 is journalled, maintains the roller in a vertical position whereby the screen is not warped when it is unwound from the roll or is wound thereonto.

To the lower end is secured the manually operated ratchet mechanism whereby the spring may be tensioned. Said mechanism includes a metal cap 22 telescopcd over the end of the roller and applied thereto. This cap closes the open end of the roller which is bored out part way in order to provide for the insertion of the rod 23 with the spring 24 wound therearound. Said spring is clamped to the rod as at 25, and the upper end of the rod is seated within a metal bearing cap 26 socketed within a key block 27 in which the end 28 of the spring is secured.

In assembling the latter described parts within the roller, the entire unit is extended to the required depth into the cavity and the screw 29 is applied through the wall of the roller and, having had its position measured to the correct distance, will penetrate the key block 27 to hold the parts securely in place. After the internal parts have been installed the metal cap 22 is applied, having been internally reinforced with the washer 30 whereby to strengthen that portion of the cap through which the rod 23 extends. At a point flush with the bottom side face of the cap 22, the rod 23 is machined to form a square shoulder 31, and beneath said shoulder throughout the remaining portion of the rod its diameter is somewhat diminished.

Onto the square shoulder thus provided is mounted the ratchet disc 32. This disc is provided with a downwardly directed circularly arranged set of ratchet teeth 33 and with a flange 34 which extends radially beyond the outside edge of said teeth. In said flange is drilled a hole 35, and there is also provided a hole of equal diameter in the cap 22 with which said hole 35 cooperates.

When it is desired to remove the screen from the roller or to repair it, the pin 36 is inserted in said holes to prevent rotation of the ratchet and thereby maintain the tension in the spring until their assembly is completed and the screen is again rolled upon the roller, whereupon the pin is removed.

Adjacent the square shoulder 31 is mounted a filler washer 37, and next is applied the ratchet lever 38. The ratchet lever has a body portion of substantially the same diameter as that of the filler washer and outwardly directed therefrom is the lever portion and manually accessible handle 39. Said lever portion is provided with an upturned lip 40 engageable with the teeth of the ratchet whereby applying manual traction to the handle, stores tension in the spring.

There is also a spring dog 41 riveted to the

bracket 19 having an upturned lip 42, engageable with the teeth of the ratchet whereby to maintain the adjusted tension in the spring. Said dog restrains the rotation of the ratchet in one direction and due to its resiliency permits depressing, thereby preventing rotation of the ratchet in the other direction.

The filler washer is of sufficient thickness in order to insure that aided by the flexibility of the handle of the ratchet, the lip 42 will over-ride the crest of the teeth as the lever is manually reciprocated. Next to the ratchet lever is applied a wearing washer 43 and therebeyond onto the stem of the rod is applied a sleeve 44 which abuts the ratchet lever to hold it and the washer 43 in place. Said sleeve is held in position by means of a screw 45 tapped into the end of the stem of the rod 23 as clearly shown in section in Fig. 2. The latter construction is also shown in Figs 3, 4 and 5.

In Fig. 3 the ratchet lever is shown sectioned where broken away, the portion of said lever which is broken away being removed in order not to conceal the lip 40 in its operative relation to the ratchet teeth.

Fig. 4 also shows the manner in which the dog 41 engages the teeth 33 of the ratchet.

In Figs. 2, 5 and 6 is shown how the lip 40 is developed into an outcurved flange 46 and provided with an aperture wherein is fastened the hook 47. There is also provided in the lower end of the end strip 11 an aperture 48 into which said hook is insertable as shown in Fig. 6 whereby the roller is held against rotation and the screen is thereby maintained in a snugly rolled condition.

As has already been stated the function of the pin 36 is to maintain the tension in the spring at any time that it is desired to partially or completely unroll the screen for the purpose of repairing or replacing it.

The entire screen, roller and adjusting device when assembled as shown in Fig. 6, may be removed bodily from its housing, simply by withdrawing the trunnion portion 15 out through the open bayonet slot and then lifting the complete device from the aperture in the bracket 19, there being sufficient clearance between the sleeve 44 and the bracket 19 to permit of a slight lateral movement of the roller so that it may be removed or replaced. In this assembled position it will be noted that the hook 47 may be connected to the side edge of the screen to keep the spring from winding the device. Therefore the pin 36 need be used only when it is not feasible to use the hook.

The pawl 39 does not extend so far from the roller as to interfere with the application of the window trim.

I claim:

1. In a device of the kind described, manually adjustable means to rotationally ad-

just a screen roller having tensioning means, said adjustable means comprising a ratchet disc rigidly fastened to the tensioning means, the teeth of said disc being directed away from the plane occupied by said disc, a washer mounted upon the face of said disc and concentric therewith, and an arm maintained by said washer in spaced relation to said disc, said arm being resilient and extending radially outward beyond said teeth, said arm being provided with a lip to cooperate with said teeth.

2. In a screen roller adjusting device, a roller, there being an axial cavity within an end portion of said roller, an adjustable tensioning rod within said cavity and projecting therefrom beyond an end of said roller, a tensioning spring operating between said rod and roller, said rod being provided with a shouldered portion, a dished ratchet disc mounted upon said shoulder portion and provided with ratchet teeth directed longitudinally outward from the roller, a manually operable pawl adapted to rotate said disc in one direction while said roller is mounted upon said bearings, and a dog to prevent reverse rotation thereof while said manual rotation thereof is being effected.

3. In a roller adjusting device, a trunnion projecting from said roller, a rotational tensioning device interposed between said roller and trunnion, a ratchet disc mounted upon said trunnion to turn therewith, a washer positioned on the outer face of said disc, a manually operable ratchet arm through which said trunnion extends, a sleeve mounted upon said trunnion outwardly from said arm, and means to retain said sleeve upon said trunnion with its inner end abutting said arm, said arm being resilient to allow it to spring toward and from the teeth of said ratchet and being furnished with a lip to cooperate with said teeth.

HANS PETER GRONBECH.
